D12-20. OR D 13,432 EX

No. 13,432

NOV 14, 1882

UNITED STATES PATENT OFFICE.

JOHN L. POPE, OF CLEVELAND, OHIO.

DESIGN FOR A SPRING AND AXLE BLOCK.

SPECIFICATION forming part of Design No. 13,432, dated November 14, 1882.

Application filed August 2, 1882. Term of patent 14 years.

To all whom it may concern:

Be it known that I, JOHN L. POPE, of Cleveland, in the county of Cuyahoga and State of Ohio, have invented and produced a new and original Design for the Spring and Axle Blocks of Carriages and other Vehicles, of which the following is a specification, reference being had to the accompanying engraving, forming part thereof.

My invention relates to a design for the spring and axle blocks of carriages and other vehicles; and it consists in the shown shape of the thing, as will be hereinafter pointed out and claimed.

In the accompanying engraving it will be seen that the edges of the block are curved

and meet at *aa*, forming pointed arch-like ends, while the edges of the ear like portions *b* and upwardly-projecting parts *c c* are similarly curved, these forming the characteristic features of my invention.

What I desire to claim by Design Letters Patent is—

A spring and axle block of substantially the shape shown.

In witness whereof I have hereunto set my hand this 17th day of July, 1882.

JOHN L. POPE.

In presence of—

L. S. FISH,
FRANK N. WILCOX.
